UNITED STATES PATENT OFFICE

172,170

PILOTLESS AIRCRAFT

I. Nevin Palley, Lancaster, Calif., assignor, by
mesne assignments, to Chance Vought Aircraft
Incorporated, a corporation of Delaware

Application March 22, 1951, Serial No. 14,595

Term of patent 14 years

(Cl. D71—1)

To all whom it may concern:

Be it known that I, I. Nevin Palley, a citizen of the United States of America, residing at Lancaster, county of Los Angeles, State of California, have invented a new, original, and ornamental Design for Pilotless Aircraft, of which the following is a specification, reference being had to the accompanying drawings, forming a part hereof.

Fig. 1 is a side elevational view of the aircraft, showing my new design;

Fig. 2 is a top plan view;

Fig. 3 is a front elevational view;

Fig. 4 is a perspective view of the aircraft, looking down from the right rear; and

Fig. 5 is a perspective view of the aircraft, looking up from the right rear.

I claim:

The ornamental design for a pilotless aircraft, substantially as shown.
